UNITED STATES PATENT OFFICE.

HENRY J. GILBERT, OF SAGINAW, MICHIGAN, ASSIGNOR TO SAGINAW MANUFACTURING CO., OF SAGINAW, MICHIGAN, A CORPORATION.

SPLIT PULLEY.

Application filed July 21, 1924. Serial No. 727,285.

This invention relates to split pulleys. The improvement pertains to certain novel constructions and combinations of parts whereby a pulley is produced that complies with all of the following requirements of service: lighter weight, increased strength to resist stresses caused by belt pull and shaft torque, better coaxial alinement of the rim and shaft, improved running balance, avoidance of sidewise wabbling or weaving of the rim when in motion, avoidance of flat places in the pulley face between the spokes, and rim bulges at the ends of the spokes, more effective hub grip on the shaft, a hub construction that renders all bolts easily accessible for tightening, and a rim construction that secures freedom from objectionable internal strains in the spokes and hub, as well as in the rim itself.

Another object of my invention is to produce a pulley adapted to rapid and economical quantity production in various diameters and widths, conforming to a new scheme or standard unit plan of split pulley construction.

With the foregoing and certain other objects in view which will appear later in the specifications, my invention comprises the devices described and claimed and the equivalents thereof.

In the drawings, Fig. 1 is a perspective view of a pulley embodying my improvements.

Fig. 2 is a fragmentary detail of the rim and a spoke separated.

Fig. 3 is a perspective view of one half a pulley embodying two sets of spokes and hubs.

Fig. 4 is an enlarged longitudinal section through a half hub.

Fig. 5 is a side view showing the hub and spokes, the rim removed.

Fig. 6 is a detail of a modified form of riveting ear for the rim reinforcing rib.

Fig. 7 is a further modified form.

Fig. 8 is a section through the hub in the plane of the clamping bolts.

Fig. 9 is a side view of the hub.

In carrying out my invention I employ the usual elements of a split pulley, namely, a sheet metal rim, spokes, a hollow shell-like split hub, and clamping bolts. I have made improvements in those various elements, and my present invention resides in the novel construction and combinations of the improved related parts.

Referring to the drawings, 1 is the split

rim, preferably formed of sheet metal and having an internal reinforcing rib 2 integral therewith.

Ears 3 on the rib 2 constitute riveting lugs for the spokes and are important features of my improved pulley. They have to do with the accuracy of the pulley, its strength, and freedom from rim strains, as will appear later.

The hub, both as to its construction and its mode of operation in gripping the shaft has novel features that form an important part of the pulley as an operating unit. It is made in two parts 4, 5, each comprising, as shown in Figs. 3 and 4, a pair of collars or shaft-gripping members 6, 7, spaced apart lengthwise as at 8. A thin-walled housing 9, preferably of U-shaped cross section connects the members 6 and 7.

The hub housing 9 has spoke-receiving faces 12 on its outer wall. These faces are in line with the respective riveting lugs 3 on the rim, as indicated in Fig. 4 by dotted line 13-13. A straight spoke 14, when fitted to an ear 3 at one end will lie flat on the corresponding face 12 of the hub at the other end. The spoke, therefore, can be applied and riveted or otherwise secured at both its ends 15, 16, without having to be forced or sprung into place, and without setting up any twisting or bending strains in the rim or in the hub.

Hub members 4 and 5 are clamped upon the shaft, not shown, by the usual bolts 10, 11.

Heretofore when a pulley has been located with one side close to a wall, a post or a shaft bearing, access to the bolt on that side was difficult if the adjacent heads or nuts were in the same plane on the hub. In consequence it has frequently happened that the hub has not been properly tightened on the obstructed side and slippage of the pulley on its shaft, with consequent wear and damage has resulted. My improved arrangement of the bolt-seats on the hub, which will now be described, avoids this difficulty by making it easy to tighten all the bolts.

Each hub section 4, 5 has two or more apertured seats 17, 18 that receive the clamping bolts 10, 11. As shown in Figs. 1 and 5, the seats are offset or stepped so the nut or head of one bolt, as 10, is seated above the head or nut of the adjacent bolt 11. Consequently it can be turned by an ordinary wrench worked from either side of the pulley and the end of the adjacent bolt can not in-

terfere with the wrench. In Fig. 8, sheet 2, one of the bolts, as 10, has its raised seat in staggered relation to seat 17 on the opposite hub member 5, thereby making the nuts of both bolts equally accessible.

The hub clamping bolts are arranged close to the shaft opening and in the space between the gripping collars 7, 8. This arrangement permits a smaller hub to be employed, yet 10 the shaft is gripped tighter with less resultant strain on the hub housing. In Figs. 3 and 9, 10^a and 11^a are the holes for bolts 10 and 11, located between the two longitudinally spaced shaft-gripping members 6 and 7. The 15 bolt holes are very close to the bore of the hub, as shown in Fig. 9. Since the whole clamping force of the bolts is applied to the hub at place as close as possible to the shaft, the tendency to spring or bend the hub housing when bolting up is thereby reduced. 20 Consequently a hub of relatively light construction can exert great gripping pressure upon the shaft, and in a most direct and effective way. The offset bolt arrangement 25 above referred to is described and claimed in my co-pending application, Serial No. 727, 284.

Within the hollow shell or housing 9 and in the space 8 between the clamping members 30 6 and 7 there is ample room for manipulating a holding-on tool while the spoke rivets 16 are being driven.

The spokes 14 are spaced around the hub and rim, see Fig. 5, so as not to hinder access 35 to the heads and nuts of all the bolts from either side of the pulley. Preferably the spokes are cut to length from straight rolled bars of suitable cross section, although they may be made from sheet metal folded to the 40 desired section.

The form of spoke-section shown in Fig. 2 is well adapted to exert maximum resistance 45 against bending in any plane. It also has relatively large riveting area, yet minimum width, and its air resistance is negligible.

Various spoke arrangements may be adopted. For example, if a single rib 2 is used two spokes are arranged convergent and secured at their outer ends to the same ear, as 50 in Fig. 1. The spread of the spokes measured along the axis of the shaft, as at 8^a, Fig. 4, is by this arrangement as wide as possible. Consequently the spokes and hub together 55 form a triangle with its apex at the rim 2 and having maximum width of base for a given length of hub. Thereby all tendency to weave is eliminated and lateral stiffness is imparted to the pulley.

Extra strong pulleys designed for very 60 wide belts preferably employ two or more structural units, Fig. 3, each comprising a hub and spokes. Obviously any number of such units may be used to make a pulley of any desired width of face.

65 The rim 1 and the purpose of its reinforce-

ing rib 2 with ears 3 thereon will now be described.

It has been customary heretofore to make the reinforcing ribs of considerable depth 70 radially so as to give sufficient support for the rim 1, and also to provide adequate riveting area for affixing the spokes. But ribs of any considerable depth have certain serious disadvantages. For example, when the sheet metal rim 1, having been folded to proper 75 cross-sectional shape is rolled or pressed into a semi-circle, the inner edge of the rib 2 is decreased in circumference and is subjected to compression. If the rib 2 is deep this results in the forcible distortion of the rib by 80 forming crinkles or corrugations along its edge as shown at 2^a in Fig. 1. Objectionable internal strains are thereby set up in rim 1, as evidenced by the distortion of the edge of 85 the rib. Strains of that kind are serious because they weaken the rim and produce in it an ever-present tendency to deform or twist out of shape. They reduce the strength of the assembled pulley so that it is likely to fail even when subjected to working loads 90 well within the safety factor for which it was originally designed.

The usual practice has been to correct the 95 rib deformation by forcibly flattening the crinkles 2^a in subsequent die-forming or pressing operations. But instead of relieving the stresses already produced, other and even more severe internal strains are thereby set up in the rim 1.

Even if a deep rib does not actually crinkle 100 when the rim is rolled to shape it will nevertheless cause stresses and faults in the rim 1. The internal stresses, of which crinkling is the visible evidence, can be largely avoided by making the ribs 2 narrow, that is, of merely 105 sufficient depth to provide the necessary interior support for the rim. That, however, entails sacrificing some of the riveting area necessary to accommodate the number of rivets required at the spoke ends. Gusset 110 plates and various other expedients, as for example, widely forked or flattened spoke ends, have been applied to narrow or shallow ribs in an attempt to secure the requisite riveting 115 area, but such constructions involve a large amount of work and introduced inaccuracies of alignment as well as internal strains in the spokes and rim. It is a purpose of my improved rib construction to avoid those defects, yet secure all the advantages of a deep rib. 120

I make that part of the internal rib 2 between the spokes of moderate depth, sufficient to give adequate rim support between the spokes, yet shallow enough to avoid appreciable crinkling, and at the points of attachment of the spokes to the rim the depth of the rib is increased to form ears 3. The length of ear 3, measured circumferentially, is approximately equal to the width of a spoke. Hence the ear will not crinkle to any 125

great degree when the rim is being formed to semi-circular shape, and such crinkling tendency as does develop is relieved preferably by being diverted to the forming of one or more radially disposed laterally projecting ridges, 3^a, on the face of each ear 3.

The relief afforded by the ridging or bulging of the ear at 3^a obviously prevents the development of undesirable internal stresses in the rim at that point. Consequently the rim can be rolled as truly circular at the ears 3 as it is between the spokes 14. The ridge 3^a also may be utilized to lock the spoke against sidewise movement, the spoke itself being 15 preferably formed with a longitudinal groove 3^b to receive the ridge 3^a.

Various means may be employed to provide the relief above referred to and thereby prevent undesirable reactionary buckling or 20 bulging stresses in the rim where the ears 3 are located.

In Figs. 2, 6 and 7 I have shown three of the ways in which this result may be accomplished. In Fig. 2 the ridge 3^a is started by 25 forming an incipient bulge in ear 3 before the rim is rolled to its final circular shape. The compression of the metal in ear 3 produced by bending the rim results in further bulging at 3^a and consequent relief of the internal 30 strains that would otherwise be set up in the rim.

In Fig. 7 the ear 3 is apertured as at 3^d before the rim is bent to shape. This removal of metal relieves or prevents the establishing of compressive strains within the ear 3 and in the absence of such strains the rim can be rolled true and smooth. The strength of the ear is not harmfully reduced by the aperture 3^d, because the spoke end when 40 riveted to the ear provides the requisite amount of reinforcement. In Fig. 6 a small area on ear 3 has been made thinner by grinding or otherwise at 3^e, prior to rolling the rim. A bulge is formed in this case, as in 3^a of Fig. 45 2. The effect of reducing at 3^e is similar to that obtained by preliminary bulging.

By the means herein set forth true running pulleys of great strength, with rims free from inherent tendency to spring or deform 50 are produced. No harmful internal strains are set up in the hubs or spokes when the parts are riveted together, because no prying or springing is resorted to and no distortion occurs during the operations of forming, assembling and riveting.

Standardization of parts is rendered possible by my invention, which makes it feasible to keep a supply of straight bars of spoke material in stock, from which to cut spokes 60 to length as needed. A single hub pattern supplies the hubs for several sizes of pulleys. The spoke requirements of a considerable range of pulley sizes is satisfied by merely varying the number of spokes.

65 The full strength of material in rim and

spokes is available to perform useful work because the non-crinkling rib 2 and the relieved integral ears 3 eliminate all objectionable internal stresses. Consequently the spokes and rim, as well as the hub, can be 70 lighter for given duty and safety factor.

Pulleys made as herein described are truly circular and coaxial with the shaft and have correct running balance because the rim assumes true circular shape when rolled, whereas pulleys in which severe internal strains are set up during the rim-forming operation or during the spoke assembling and riveting operations almost invariably have flat places and bulges in their rims.

Since there are no internal strains tending to throw the rim and spokes out of alignment, absence of weaving or wobbling is an especially notable characteristic of these pulleys. The stepped and lengthwise offset bolt arrangement and the location of the spokes with relation to the bolts makes the nuts and bolt heads so readily accessible that nothing short of negligence will account for a hub improperly clamped to its shaft. Consequently in 90 practice slippage of the hub on the shaft almost never occurs when these pulleys are used.

The broader aspects of the combination of devices that comprises the completed pulley 95 are described and claimed herein, and the specific improvements in the various elements are set forth and claimed in certain of my co-pending applications.

Having thus described my invention what I 100 claim and desire to secure by Letters Patent is:

1. A pulley comprising half-rims, each formed of a single piece of folded sheet metal rolled to semi-circular shape and having an 105 internal rib of shallow radial depth and inwardly projecting ears integral with each rib, a pair of hub sections each comprising two shaft-gripping members spaced apart lengthwise, a housing consisting of a hollow 110 annular shell of U-shaped section connecting said members, clamping bolts through said hub sections at places intermediate said spaced gripping members and located in longitudinally offset relation, spoke-receiving 115 faces on the outer walls of said housing, each face disposed in a plane that includes one of said ears, and spokes, each secured at its outer end to one of said ears and at its inner end to one of said spoke-receiving faces.

2. A pulley, comprising a rim and a hub, an inwardly projecting rib on said rim, a radial ridge in said rib, a spoke connecting said hub and rim, and said spoke having a channel disposed longitudinally thereof to 125 snugly receive said ridge, and fastening means for said spoke and rib.

In testimony whereof, I affix my signature.

HENRY J. GILBERT.
